(57) **CLAIM**

We claim the ornamental design for a semiconductor manufacturing equipment, as shown and described.

DESCRIPTION

FIG. 1 is a front, top and right side perspective view of an semiconductor manufacturing equipment showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing of the “semiconductor manufacturing equipment” is for the purpose of illustrating environmental structure and forms no part of the claimed design.
